BRAKE HEAD WEAR ELEMENT

Filed Feb. 26, 1940

UNITED STATES PATENT OFFICE

2,250,637

BRAKE HEAD WEAR ELEMENT

Malcolm S. Johnson, Chicago, Ill., assignor to
 Illinois Railway Equipment Company, Chicago,
 Ill., a corporation of Illinois

Application February 26, 1940, Serial No. 320,921

5 Claims. (CL. 188—236)

My invention relates to a self-locking wear take-up and wear resisting element adapted to the standard type of brake head and brake shoe for the purpose of firmly anchoring the shoe to the brake head against vibration and wear producing movement between the head and shoe during train operation.

The invention has for its object the provision of a single piece element adapted to take up wear previously encountered by the shoe-lug engaging lugs of the brake head so as to provide the comparatively snug relation between the brake head and shoe required by the A. A. R. rules and thereby enabling the brake head to be continued in service; preventing further wear of the brake head and maintaining the required distance between the upper and lower lugs of the head.

The invention also has for its object the provision of an element which may be easily applied to brake heads in use, even though more or less worn, constructed to permit the brake shoe key to pass therethrough and effect wedging relation with the key to prevent its accidental movement into shoe unlocking position; the element being constructed to effect locking engagement with the brake head to prevent its loss in the event of removal of the brake shoe; the element at the same time preventing disengagement between the brake head and the hanger.

The enumerated objects, as well as others, and the advantages of my invention will all be readily comprehended from the detailed description of the accompanying drawing wherein:

Figure 1 is a perspective view of my improved wear element as viewed from its rear.

Figure 2 is a perspective view of the forward shoe receiving face of a brake head illustrating a worn shoe supporting lug.

Figure 3 is a similar view of the forward face of a brake head with the lower portion broken away and showing my wear element applied to the shoe retaining lugs.

Figure 4 is a vertical sectional view, somewhat enlarged, of portions of the head lugs with the wear element applied and a portion of the shoe locking key inserted in place.

Figure 5 is a perspective view of one of the supplemental sections shown applied in Figure 3 and employed with excessively worn lugs as disclosed in Figure 2.

My improved wear element is intended for the standard type of brake heads and shoes at present in use on railroads and is so constructed that it can be easily applied, whether the head is new or

worn, without necessitating change or alteration in the head and shoe construction; the wear element normally being constructed to be reversible and to enable application without need for special tools or skill.

The heads and shoes generally consist of more or less rough castings with certain tolerances in manufacture to enable easy insertion of the shoe lug (not shown) between the vertically spaced lugs 10, 11 of the brake head 12 and as a result it is never possible under such conditions to obtain a tight fit between the brake shoe and the brake head; in fact the tolerances are such that an undesirable excess play between the brake head and shoe lugs is encountered which permits the shoe to vibrate in an up and down movement when the train is in motion. Brake shoes are of hard cast iron while the brake heads are of malleable iron and hence softer material, with the weight of the comparatively heavy shoe being carried by the lower supporting lug of the brake head. With these conditions and the constant movement or vibration of the shoe the head lugs and particularly the lower shoe supporting lugs 11 of the brake heads readily become badly worn on their upper surfaces as shown at 13 in Figure 2; the wear rapidly increasing in proportion to the amount of play between the lugs of the head and the shoe, permitting excess travel of the shoe independently of the head during brake application which causes the shoe lug to cut into the head lugs and to produce wear at the contact points between the rear of the shoe and the forward face of the brake head lugs. The excessive play and wear mentioned greatly reduces the useful period of the brake head and necessitates the undesirable expense and labor of frequent brake head renewal.

My improved one-piece wear element 14, shown in Figure 1, preferably is stamped out of a hard metal plate or sheet steel to provide the two similar lug protecting plate sections 15, 15 arranged substantially parallel with each other and held in predetermined spaced relation by the connecting strap section 16 which is integral with the rear edges of the plate sections; the plate sections 15, 15 being spaced from each other in keeping with the spacing between the upper and lower lugs 10 and 11 of the brake head so as to snugly fit therebetween, as shown in Figures 3 and 4.

The plate sections 15, 15 are of length corresponding with the widths of the head lugs 10, 11, with straight forward edges in keeping with the forward sides of the head lugs and with the intermediate portions of the plate sections off-

set in a vertical direction toward each other as shown at 17; these offset portions extending from front to rear and being of width corresponding to the distance between the usual laterally spaced lugs of the shoe without, however, interfering or contacting with the usual connecting strap between the shoe-lugs. The rear longitudinal edges 18 of the plate sections 15 are shown arcuate to correspond to the usual curved sides of the shoe lugs; thus also adapting the wear element to the depression worn into the faces of the head lugs by the shoe lugs.

The intermediate off-set portions 17 of both plate sections 15 are provided with slots or openings 19 arranged to register with the locking key receiving passages in the lugs 10 and 11 of the brake head as well as with the passage in the shoe lug; the openings 19 being of size sufficient to permit the shoe locking key, of which a portion is shown at 20 in Figure 4, to pass therethrough.

The openings 19 in the plate sections are cut so as to leave the tongues 21 integral with the forward sides of the openings 19 and these tongues 21 are bent in opposite directions toward the outer faces of the plate sections 15, so as to be disposed, respectively, upwardly and downwardly as shown in Figure 1 and permit one tongue 21 to enter into the key receiving opening in brake head lug 10 and the other tongue 21 to enter the key receiving opening in the lower brake head lug 11; the tongues 21 effecting locking engagement with the head lugs. With the wear element 14 stamped from sheet steel it possesses sufficient resiliency to 35 permit it to be forced between the head lugs 10 and 11 and allow the tongues to spring into the key receiving holes in the head lugs, with the tongue of the upper plate section arranged flush with the forward side of the key slot in the upper lug 10 as shown in Figure 4, while the tongue 21 of the bottom plate section initially is arranged at a slight angle to the forward wall of the key slot in head lug 11, as shown in dotted lines in Figure 4, so as to effect frictional 40 locking engagement with the shoe locking key 20 when the latter is driven downwardly through the lugs 10 and 11 of the brake head and through the intervening lug of the brake shoe whose lug (not shown) engages the opposing faces of the two plate sections 15, 15, which maintain the shoe lug out of contact with the head lugs.

The connecting strap section 16, as shown in Figures 3 and 4, will be disposed rearward of the shoe lug and extend vertically across the hanger receiving socket 22 in the brake head and consequently will prevent the hanger-link moving out of the socket 22 when occasion requires the shoe to be removed; the wear element 14 maintaining its self-locking engagement with the brake head.

As previously stated, the lower lug 11 which supports the weight of the brake shoe is subjected to the greatest wear and in the event the lower lug 11 becomes excessively worn requiring a plate section 15 of greater thickness, the lower plate section of my improved wear element may then be provided with two triangular supplemental sections 23, as shown in Figure 5, which 70 match the portions of the plate section 15 on opposite sides of the intermediate off-set portion 17; these triangular sections 23 being made of sheet steel of the necessary thickness and being preferably welded to the outer face of the 75

lower plate section 15 of the element as shown in Figure 3.

It will be understood that my improved wear element is adapted for use with new or unworn 5 brake heads at which time the supplemental sections 23 generally would be omitted, the latter being merely employed in the event of considerable brake head wear.

With my improved wear element positioned 10 as shown and described, it is apparent that the space between the shoe lug and the head lugs 15 will be filled and prevent vibratory movement, while the space between the forward face of the key 20 and the forward walls of openings in head lugs 10 and 11 also will be partially filled and cause the shoe to be drawn backward against the forward face of the head into snug relation therewith, with the result that the up and down play between shoe and head lugs will be eliminated and the thrust of the shoe lug will be absorbed by the steel wear resisting element 14 and the period of usefulness of the brake head greatly enhanced while at the same time preventing undesirable movement of the shoe locking key.

The exemplification is believed to be the best embodiment of the invention which has been described in terms employed for purposes of description and not as terms of limitation, as modifications may be possible without, however, departing from the spirit of my invention as defined in the appended claims.

What I claim is:

1. A reversible brake head wear element comprising a pair of similar plate sections connected together in spaced apart and substantially parallel relation by a narrow strap section arranged at one longitudinal side of the element and intermediate of the ends of the plate sections, the 40 plate sections intermediate of their ends having aligned key receiving openings and integral tongues adjacent said openings and disposed in opposite directions whereby the element is secured to the brake head against displacement.

2. A wear element for the vertically spaced lugs of a brake head provided with a hanger receiving socket open at the forward side of the head intermediate of said lugs comprising a pair of vertically spaced apart plate sections adapted to bear against the opposing shoe-lug supporting faces of the brake head lugs, and a resilient strap section integral with the rear longitudinal edges of the plate sections adapted to extend vertically across the open forward side of the hanger socket 50 in the brake head and to yieldingly hold the plate sections in spaced relation.

3. A wear element for a shoe holding brake head adapted to be disposed between the vertically spaced apart lugs of a brake head and comprising a pair of spaced apart similar plate sections adapted to bear against the lower and the upper faces of the respective brake head lugs, said plate sections being provided with key-receiving openings and with oppositely disposed key-engaging tongues, and a resilient strap section connected to the rear longitudinal edges of the plate sections intermediate of their ends whereby the plate sections are maintained against the opposing faces of the brake head lugs.

4. A wear element for a shoe holding brake head adapted to be disposed between the vertically spaced apart lugs of a brake head and comprising a pair of vertically spaced similar plate sections provided with registering key-receiving openings and with angularly disposed resilient

tongues at one side of said openings and extending in opposite directions and a resilient strap section integral with the rear longitudinal edges of the plate sections intermediate of the ends thereof whereby the plate sections are yieldingly held in spaced relation.

5. A reversible brake head wear element comprising a single piece member formed to provide a pair of similar plate sections vertically spaced to seat against the opposing faces of the spaced apart lugs of a brake head, the plate sections in-

termediate of their ends being provided with opposingly disposed offset surfaces adapted to effect engagement with the lug of a brake shoe, said surfaces being provided with key-receiving slots and with vertically extending resilient tongues disposed in opposite directions at one side of the slots, and a resilient strap section integral with the offset surfaces of the plate sections at the rear longitudinal edges thereof whereby the plate sections are yieldingly held in spaced relation.

10 MALCOLM S. JOHNSON.
